METHOD OF MAKING BINDERS

Philip V. Spinner, Chicago, Ill., assignor to Plastic Binding Corporation, Chicago, Ill., a corporation of Delaware

Application November 12, 1946, Serial No. 709,358

8 Claims. (Cl. 18—56)

1

This invention relates to a process of making plastic resilient binders of the type consisting of a backbone from which extend a plurality of fingers curled into a position overlapping the backbone.

It is one of the objects of the present invention to provide a process for making a binder of the above mentioned type which will permit the use of extruded tubular stock for the fabrication of the binder and which will utilize the material of the tube with a minimum of waste. In accordance with the principles of the present invention an extruded plastic tube is die cut to form two incomplete binders each of which consists of a backbone with fingers extending therefrom. The free ends of the fingers of each binder are spaced from the backbone thereof by an amount approximately equal to the width of the backbone. The two incomplete open binders are then separated from one another and each one is then fabricated to close the gap between the free ends of the fingers thereof and the backbone. This fabrication consists in forcing the free ends of the fingers and the back together either into abutment or into overlapping relationship as desired, and applying heat to the binder while it is being thus formed, so that upon cooling of the binder the binder retains the shape to which it has been formed, namely, that of closed rings held together by a backbone.

The attainment of the above and further objects of the present invention will be apparent from the following specification taken in conjunction with the accompanying drawing forming a part thereof.

In the drawing:

Figure 1 is a perspective view of a tube blanked in accordance with the present invention;

Figure 2 is a sectional view of the tube of Figure 1, taken along the line 2—2 of Figure 1;

Figures 3 and 4 are perspective views of two incomplete binders which result from separation of the cut tube as in Figure 1;

Figure 5 illustrates, diagrammatically, the manner of completing the binder of Figures 3 and 4;

Figure 6 is a fragmentary perspective view of a completed binder;

Figure 7 is a fragmentary view corresponding to Figure 5 and showing an alternate method of completing the binder of Figure 4 or 5; and

Figure 8 is a sectional view through the binder completed by the process of Figure 7.

Reference may now be had more particularly

to the drawings wherein like reference numerals designate like parts throughout.

The binder of the present invention is made from an extruded cylindrical tube of Celluloid, cellulose acetate, pyroxylin, Vinylite or other thermoplastic resilient material. The tube 1 is cut to form two binders. The cut is along a longitudinally extending sinusoidal line 2 and along lines of cut 4 which extend circumferentially of the cylinder, each line of cut 4 extending through an arc less than 360°. The cylindrical lines of cut 4 are joined by lines of cut 5 and 6 which are spaced on opposite sides of the sinusoidal line 2 to provide fingers 8 and 10 extending respectively from two lengthwise extending backbones 7 and 9 which abut on opposite sides of the sinusoidal line of cut 2. After the cylinder has been cut in the manner indicated in Figure 1 the cut parts are separated to provide two similar incomplete binders illustrated in Figures 3 and 4. Each of the incomplete binders has a backbone 7 or 9 from which extend the curled fingers 8 or 10, as the case may be, forming almost but not quite closed loops. The spaces between the free ends 5 of the fingers 10 and the backbone 9 in Figure 3 are exactly equal to the width of the backbone 7 of the incomplete blank of Figure 4, and the spaces between the free ends 6 of the fingers 8 of the backbone 7 of Figure 4 are the spaces that were occupied by the backbone 9 of Figure 3. There is thus produced two substantially identical binders each of which is incomplete in that there is a gap between the free ends of the fingers thereof and the backbone.

35 The binders of Figures 3 and 4 may then be completed in the following manner: Inside the incomplete binder is placed a cylinder rod 20 which is of a circumference smaller than that of the original extruded cylindrical blank 1. The rod 40 with the binder therein is then placed in a machine which includes a table 21 and two movable heated dies 22—23 which are movable towards and from one another and which include heated concave semi-cylindrical surfaces 25—26. The dies are then moved towards one another and towards the arbor 20. The die surfaces 25 and 26 force the fingers 10 and the backbone 9 towards one another. The diameter of the rod 20 chosen and the radii of the curved surfaces 25 and 26 are so related to the specific size of the blank of Figure 3 that when the dies 22—23 are brought together the free ends 5 of the fingers 10 are moved into a position exactly abutting the backbone 9. The dies heat the binder to a temperature which is not high enough to make

the material tacky but sufficiently high to impart a permanent set thereto upon cooling. This results in the production of a binder such as shown in Figure 6, wherein the binder is of a circular cylindrical shape and of a diameter slightly less than the diameter of the original blank tube 1 and wherein the edges of the free ends of the fingers 10 bear against the edges of the outside of the backbone 9.

If it is desired to produce a binder wherein the fingers overlap the backbone, from an incomplete binder such as shown in Figure 3, it is merely necessary to use a cylindrical rod 20' which is of somewhat smaller diameter than the rod 20 and to use corresponding dies 22'-23', the curved surfaces 25' and 26' of which are also of somewhat smaller diameters than the diameters of the corresponding curved parts of the dies of Figure 5. This is illustrated in Figure 7. In this case the cylindrical rod 20' around which the blank of Figure 3 is placed is held stationary, and the heated die 23' is first moved towards the cylindrical rod 20'. This forces the backbone of the binder into intimate contact with the rod 20', the surface 26' being of a radius greater than the radius of the rod 20' by the thickness of the blank. Thereafter the die 23' is retracted and the heated die 22' is moved to the right of the position shown in Figure 7 and then moved downwardly. The die 22' is moved to the right until the straight part 27 of the die has forced the finger 10 against the rod 20'. At this time the upper right hand part of the curve 25' has forced the finger 10 over and above the backbone 9. The right hand end of the curve 25', indicated at 28, is at a height above the rod 20' by an amount slightly more than necessary to clear twice the thickness of the blank material. Thereafter the die 22' is moved downwardly thereby forcing the last 90° of the fingers 10 into a circular shape with the ends of the fingers in firm contact with the portions of the backbone overlaid thereby. Thereafter the die 22' is first raised and then retracted. The rod 20' with the curled binder thereon is removed from the machine and, after cooling of the binder on the rod the binder is removed from the rod. This results in the production of a binder of a cross section such as shown in Figure 8, wherein the fingers 10 overlap the backbone 9.

The incomplete binder of Figure 3 or 4 may be formed into a complete binder such as shown in Figure 6 or 8 by steps different from that illustrated in Figures 5 and 7. For instance, the incomplete binder of Figure 3 may be rolled to completion by inserting thereinto the circular arbor or rod 20 or 20' as the case may be and then rolling the arbor with the incomplete binder around it in a machine of the type illustrated in the patent to C. B. Nelson and I. Spinner, No. 2,211,744, issued August 13, 1940. The manner in which this may be done is described in that patent.

In compliance with the requirements of the patent statutes I have here shown and described a preferred embodiment of my invention. It is, however, to be understood that the invention is not limited to the precise steps here shown, the same being merely illustrative of the principles of the invention.

What I consider new and desire to secure by Letters Patent is:

1. The method of making a tubular plastic binder of the type comprising a backbone from which extend a plurality of curled spaced apart

fingers which comprises, providing a plastic resilient tube cut to form two longitudinally extending backbones from each of which extends the fingers to form a binder and with the fingers of each binder extending into the spaces between fingers of the other binder, then separating the tube along the lines of cut to provide two incomplete tubular binders each with the fingers and backbone thereof extending through an arc which is open by an amount substantially equal to the width of the backbone of the other binder, then forcing the fingers of the separated incomplete binders to a position closing said opening and applying heat to each binder in an amount sufficient to cause the fingers thereof to remain in the closing position after cooling, then cooling the same.

2. The method of making a tubular plastic binder of the type comprising a backbone from which extend a plurality of curled apart fingers which comprises, providing a plastic resilient tube, then cutting the tube to form two longitudinally extending backbones from each of which extends the fingers to form a binder and with the fingers of each binder extending into the spaces between fingers of the other binder, then separating the tube along the lines of cut to provide two incomplete tubular binders each with the fingers and backbone thereof extending through an arc which is open by an amount substantially equal to the width of the backbone of the other binder, then forcing the fingers of the separated incomplete binders to a position closing said opening and applying heat to each binder in an amount sufficient to cause the fingers thereof to remain in the closing position after cooling, then cooling the same.

3. In the art of making a tubular plastic binder of the type comprising a backbone from which extend a plurality of curled spaced apart fingers, the steps which comprise, providing a plastic resilient tube, then cutting the tube to form two longitudinally extending backbones from each of which extends the fingers to form a binder, and with the fingers of each binder extending into the spaces between fingers of the other binder, then separating the tube along the lines of cut to provide two incomplete tubular binders each with the fingers and backbone thereof extending through an arc which is open by an amount substantially equal to the width of the backbone of the other binder.

4. The method of making a tubular plastic binder of the type comprising a backbone from which extend a plurality of curled spaced apart fingers which comprises, providing a plastic resilient tube cut to form two longitudinally extending backbones from each of which extends the fingers to form a binder and with the fingers of each binder extending into the spaces between fingers of the other binder, then separating the tube along the lines of cut to provide two incomplete tubular binders each with the fingers and backbone thereof extending through an arc which is open by an amount substantially equal to the width of the backbone of the other binder, then closing said openings.

5. The method of making a tubular plastic binder of the type comprising a backbone from which extend a plurality of curled spaced apart fingers which comprises, providing a plastic resilient tube cut to form two longitudinally extending backbones from each of which extends the fingers to form a binder and with the fingers

of each binder extending into the spaces between fingers of the other binder, then separating the tube along the lines of cut to provide two incomplete tubular binders each with the fingers and backbone thereof extending through an arc which is open by an amount substantially equal to the width of the backbone of the other binder, then forcing the fingers of the separated incomplete binders to positions closing said openings.

6. The method of making a tubular plastic binder of the type comprising a backbone from which extend a plurality of curled spaced apart fingers which comprises, providing a plastic resilient tube, then cutting the tube to form two longitudinally extending backbones from each of which extends the fingers to form a binder and with the fingers of each binder extending into the spaces between fingers of the other binder, then separating the tube along the lines of cut to provide two incomplete tubular binders each with the fingers and backbone thereof extending through an arc which is open by an amount substantially equal to the width of the backbone of the other binder, then closing said openings.

7. The method of making a tubular plastic binder of the type comprising a backbone from which extend a plurality of curled spaced apart fingers which comprises, providing a plastic resilient tube, then cutting the tube to form two longitudinally extending backbones from each of which extends the fingers to form a binder and with the fingers of each binder extending into the spaces between fingers of the other binder, then separating the tube along the lines of cut to provide two incomplete tubular binders each with the fingers and backbone thereof extending

through an arc which is open by an amount substantially equal to the width of the backbone of the other binder, then forcing the fingers of the separated incomplete binders to positions closing said openings.

8. The method of making a tubular plastic binder of the type comprising a backbone from which extend a plurality of curled spaced apart fingers which comprises, first forming a pair of incomplete tubular binders with the fingers and the backbone of each incomplete binder extending through an arc less than 360° by an amount substantially equal to the arcuate extent of the backbone, and with the fingers of each incomplete binder extending between the fingers of the other and abutting the backbone thereof, then separating the incomplete binders of the pair, then forcing the fingers and backbone of each incomplete binder to a loop closing position and applying heat to the binder in an amount sufficient to cause the binder to remain in said closing position after cooling, and then cooling the same.
